ROLLING MILL

Joseph D. Kiss, Detroit, Mich.

Application July 3, 1948, Serial No. 36,949

2 Claims. (Cl. 153—54)

1

This invention relates to metal-working machinery and in particular to rolling mills for forming elongated metal articles by rolling operations upon sheet metal stock.

One object of this invention is to provide a universal rolling mill composed of a series of metal rolling units which perform rolling operations in sequence upon sheet metal stock so as to form it into elongated members of the desired cross-sectional shape, each rolling machine having its rolls adjustable relatively to one another without interfering with their driving connections, thereby enabling worn rolls to be utilized by merely moving them closer together.

Another object is to provide a universal rolling mill composed of rolling units of the foregoing character wherein one of the roll shafts is mounted upon slides and is driven by a worm gear which meshes with an elongated worm so as to permit moving the shaft toward or away from the other shaft, thereby adjusting the separation of the rolls, the drive to the adjustable roll shaft being maintained during adjustment merely by causing the worm gear to roll along the elongated worm while remaining in mesh therewith.

Another object is to provide a universal rolling mill composed of rolling units having two pairs of roll shafts, one pair having its axes of rotation nearer together than the other pair, either pair being removable so that at any given time, according to the nature of the workpieces being rolled, a pair of large diameter or small diameter rolls may be employed, thereby adapting the machine to a wide range and variety of workpieces.

Another object is to provide a universal rolling mill, as set forth in the object immediately preceding, the rolls being mounted upon arbors with tapered or conical ends fitting into sockets of corresponding shape, thereby permitting the quick removal and replacement of rolls, and also enabling interchangeable arbors to be employed, according to the nature of the workpiece to be produced, these arbors being of various diameters as desired, but fitting into permanently installed roll shafts.

In the drawings:

Figure 1 is a top plan view of a rolling unit for a universal rolling mill, according to a preferred form of the invention, with a large diameter pair of rolls in use and a small diameter pair removed;

Figure 2 is a vertical longitudinal section taken along the line 2—2 in Figure 1;

Figure 3 is a vertical cross-section taken along

2

the line 3—3 in Figure 1, and showing the outboard bearing support; and

Figure 4 is a vertical cross-section taken along the line 4—4 in Figure 1, showing the mechanism for adjusting the roll separation while maintaining an uninterrupted driving connection.

Rolling mills of prior design hitherto have customarily employed rolls mounted on roll shafts which are of substantially fixed separations. The rolls are ground to accurate diameters so that they will precisely form the sheet metal stock into the desired shape. When the rolls become worn through long use, they cannot be reground and hence are ordinarily discarded and replaced by new rolls of the proper diameters, because the ordinary driving mechanism for the roll shafts is incapable of permitting the shafts to be moved closer together to compensate for the wear, much less to permit rolls of smaller diameter to be used upon the same roll shafts.

The present invention provides a rolling unit for a universal rolling machine, wherein one of the roll shafts is journaled in bearings which are mounted on slides so as to be adjustable toward or away from the other roll shaft, a driving connection being maintained, regardless of the varying separation of the rolls, by a worm gear or worm wheel on the roll shaft meshing with an elongated worm on the drive shaft. In this manner, the adjustable roll shaft may be moved toward or away from the other roll shaft in order to compensate for the wear of the rolls or to enable different sizes of rolls to be interchangeably mounted in the rolling unit. Each rolling unit is preferably also supplied with two pairs of roll shafts, mounted at different separations of their axes of rotations, each shaft having conical sockets adapted to receive the conical ends of arbors on which the rolls are removably and interchangeably mounted. Only one pair of roll shafts of each rolling unit is used at a given time. The provision of a pair of roll shafts of different separations enables a wide range of roll diameters to be employed, depending upon the work to be produced, thus giving the machine a wide adaptability to greatly differing sizes of workpieces. It is to be understood, of course, that a complete machine consists of several such rolling units arranged in sequence, each having slightly different rolls so that each unit performs part of the work of bending the sheet metal stock into the desired form by a sequence of operations performed in the one machine or rolling mill.

Referring to the drawings in detail, Figure 1

shows one unit generally designated 10 of a rolling machine 11, wherein a series of rolling units 10 are mounted in sequence along a bed or base 12 and driven from a common power source (not shown). For the purposes of the invention, it will be sufficient to describe only one of the units 10 since all units in the series are of substantially the same construction.

The rolling unit 10 includes a housing 13 and an outboard rest 14 mounted in spaced relationship to the housing 13 with the lower and upper rolls 15 and 16 supported in the space between the housing 13 and rest 14. The housing 13 is of box-like form having a bottom 17 (Figure 4) which is grooved as at 18 to receive a locating rib 19 bolted into a transverse groove 20 in the bed 12. The rest 14 similarly is provided with a bottom 21 (Figure 3) which is grooved as at 22 to receive a locating rib 23 bolted thereto and likewise mounted in the groove 20. In this manner, the housing 13 and outboard rest 14 are accurately maintained in alignment with one another. The bottom 21 of the outboard rest 14 is provided with transverse slots 25 for receiving clamping bolts 26 threaded into holes 27 in the bed 12, thereby enabling the outboard rest 14 to be slid to and fro transversely of the bed 12 and bolted in its adjusted position.

The bottom 17 and top 28 of the housing 13 (Figure 4) are provided with co-axial apertures 29 and 30 into which are bolted lower and upper bearing bushings 31 and 32 respectively. Journaled in the bores 33 and 34 of the bearing bushings 31 and 32 is a worm shaft 35 carrying lower and upper worms 36 and 37 respectively, the upper worm 37 being more elongated than the lower worm 36. The worm shaft 35 is driven by bevel gearing (not shown) at its lower end from a line shaft (also not shown) connected to a common source of power, such as an electric motor.

Meshing with the lower and upper worms 36 and 37 are lower and upper worm gears or wheels 38 and 39 respectively keyed to lower and upper large rolls shafts 40 and 41 (Figure 4). The lower large roll shaft 40 is journaled in aligned bearing bores 42 and 43 formed in the end plate 44 and the forward wall 45 of the housing 13 (Figure 2). Keyed to the lower large roll shaft 40 is a gear 46 (Figure 2) which meshes with an idler gear 47 mounted upon a stud 48 (Figures 1 and 4) threaded into the forward wall 45. The idler gear 47 in turn meshes with a pinion 49 keyed to the lower small roll shaft 50 which is journaled in the forward wall 45 of the housing 13.

The opposite side walls 51 and 52 of the housing 13 are grooved vertically as at 53 and 54 (Figure 1) to receive vertical guide ribs 55 and 56 respectively bolted therein. Suitably grooved as at 57 and 58 to receive the guide ribs 55 and 56 is a vertically movable carriage or slide 59. The slide 59 is provided with a plurality of threaded sockets 60 adapted to receive the threaded lower ends 61 of plugs 62 having internally threaded bores 63 threadedly receiving the lower ends of adjusting screw shafts 64 journaled at their upper ends in upwardly extending bosses 65. One of the screw shafts 64 at its upper end carries a graduated collar 66 which registers with a pointer 67 secured to the adjacent boss 65 in order to indicate the amount of motion imparted to the screw shaft 64 when its squared head 68 is rotated, as by a wrench.

The upper large roll shaft 41 is journaled in a bore 69 in the slide or carriage 59 and has keyed

thereto a gear 70 mounted adjacent the worm wheel 39. The gear 70 meshes with a pinion 71 rotatably mounted upon a stud 72 similar to the stud 48 and similarly threaded into the slide or carriage 59. The idler gear 71 meshes with a pinion 73 (Figure 4) keyed to the upper small roll shaft 74. The latter is journaled in a bore 75 in the slide or carriage 59. The large roll shafts 40 and 41 terminate at their forward ends in collar-like enlargements 76 with radial driving tongues or ribs 77 thereon, whereas the small roll shafts 50 and 74 similarly terminate in enlargements 78 with radial driving tongues or ribs 79. The forward ends of each of the shafts 40, 41, 50 and 74 are provided with conical sockets 80 terminating in straight or cylindrical portions 81 centrally bored and threaded as at 82 to receive the threaded end 83 of a clamping bolt 84 (Figure 2). The bore 82 in turn opens into an enlarged bore 82a. The conical sockets 80 serve to receive the correspondingly tapered rearward ends 86 and cylindrical portions 85 of arbors 87 which are of similar construction except that the arbors for the small rolls (not shown) are of course of smaller diameter to conform to the closer mounting of the smaller roll shafts 50 and 74 to one another.

The arbors 87 are bored longitudinally as at 88 for the passage of the clamping bolt 84 and are also provided with annular abutments 89 for the lower or upper large rolls 90 or 91 respectively (Figure 2). The arbors 87 are provided with keyways 92 (Figure 3) for the reception of keys 93 by which the rolls 90 and 91 are drivingly and removably mounted on the arbors 87. The outer ends of the arbors 87 are provided with conical or tapered ends 94 terminating in cylindrical portions 95. Each of the large rolls 90, 91 and also the small rolls (not shown) is bored to slide upon the central portion of the arbor 87. The rolls 90 and 91 are of any desired configuration, depending upon the workpiece to be produced and the stage which that particular pair of rolls occupies in the sequence of units 10. For purposes of illustration, but without limitation, the rolls 90 and 91 are shown as provided with a co-acting groove 90a and rib 91a, both of annular form and arranged at the same distances from the ends of the rolls 90 and 91 so that they mate with one another to provide an even spacing for the sheet metal of the workpiece W (Figure 2) acted upon by the cooperating rolls 90 and 91.

The rolls 90 and 91 are accurately ground to the same lengths, within very close tolerances, so that all of the grooves 90a and ribs 91a of the various rolls in the various rolling units 10 will be in line with one another along the rolling mill 11. The rolls 90 and 91 are held in place against the abutment 89 (Figure 2) by spacing collars 96 which in turn are engaged by annular shoulders 97 on lower and upper bearing bushings or sleeves 98 and 99 respectively. Each lower large roll sleeve 98 is journaled in a bore 100 in the lower portion of the outboard rest 14, whereas the upper large roll sleeve 99 is journaled in a bore 101 in a slide or carriage 102 slidably mounted along the vertical guide portions 103 (Figure 3) of the outboard support 14. The latter is provided with a top member 104 in the form of a bridge having an upwardly-extending portion 105 in which are journaled screw shafts 106, the lower ends of which are threaded into threaded bores 107 in plugs 108 similar to the plugs 62 previously described and having similar threaded lower ends 109 threaded into sockets 110 in the

upper portion of the slide or carriage 102. One of the shafts 106 is provided with a graduated drum or collar 111 cooperating with a pointer 112 secured to the upper portion 105 of the top member 104 to indicate the motion imparted to the screw 106. The screws 106 have squared upper ends 113 for receiving a wrench, similar to the squared upper ends 68 of the screw shafts 64.

Also journaled in the lower portion of the outboard support 14 and slide or carriage 102 respectively are lower and upper sleeves or bushings 114 and 115 respectively for the arbors of the small roll shafts 50 and 74, and mounted with their axes at the same separation (Figure 3). As previously stated, only one pair of arbors 87 is in use at a given time in a given rolling unit. Each of the bushings or sleeves 98, 99, 114 and 115 is provided with a conical socket 116 terminating in a straight or cylindrical end portion 117 adapted to receive the conical ends 94 and cylindrical portions 95 of the arbors 87. From each socket 116 a bore 118 passes outward for the passage of the clamping bolt 84. The outer end of each sleeve or bushing is of reduced diameter and threaded as at 119 (Figure 2) to receive a correspondingly threaded retaining collar 120 having a locking set screw 121 therein for securing it in position. Each of the collars 89 on the arbors 87 is provided with a radial slot 122 to receive the tongue or rib 77 so as to establish a driving connection.

Operation

In the operation of the rolling mill 11, a pair of rolls is selected from each rolling unit 10 which is appropriate to the size and nature of the workpiece to be rolled. If it is a workpiece with a very small groove or channel, small diameter rolls may be used mounted on arbors seated in the conical recesses of the small roll shafts 50 and 74 and the small roll bushings 114 and 115. If, however, the work to be rolled is large or has deep grooves, a pair of large diameter rolls 15, 16 mounted on the more widely separated shafts 40 and 41 are employed. Let it be assumed that such large rolls are employed, as shown in the drawings, the small rolls being therefore omitted, as indicated by the empty space and chain lines (Figure 1) between the members 78 and 115. It will be understood, however, that rolls up to a certain maximum diameter can be handled by the small arbors and shafts and rolls from this maximum size to a second maximum size can be handled by the second pair of more widely separated shafts 40 and 41. In one machine which the applicant built according to the invention, for example, the rolls could be handled through-out a range extending from a minimum diameter of three inches to a maximum diameter of ten inches, thus giving the machine a versatility not found in ordinary rolling mills.

The operator now turns on the power, causing the various vertical shafts 35 (Figure 4) to be rotated from their preferably common power source or from independent power sources, as desired. As the shafts 35 rotate, their rotation is imparted through the worms 36 and 37 to the worm wheels or worm gears 38 and 39 and accordingly to the lower and upper large roll shafts 40 and 41. If, however, the lower and upper small roll shafts 50 and 74 are in use, these are driven in the same manner, the drive from the shafts 40 and 41 being continued through the gears 46 and 70 thereon, thence through the idlers 47 and 71 to the pinions 49 and 73 mounted on the lower

and upper small roll shafts 50 and 74 respectively (Figure 4).

With the large rolls 15 and 16, for example, in place in each rolling unit 10, and with the various rolling units so adjusted and the rolls so configured that each pair of opposed rolls performs a partial bending step upon the workpiece, a strip of metal is started through the first pair of rolls and receives its initial bend, receiving a further bend between the second pair of rolls, a still further bend between the third pair, and so on, until the workpiece W is completely formed, so far as the rolling mill is concerned. The rolls 15, 16 may of course be adjusted as to separations by rotating the screws 64 and 106 in appropriate directions, thereby widening or narrowing the space between the opposed rolls 15 and 16. As this adjustment is made, the drive is uninterrupted (Figure 4) either to the large roll shafts 40, 41 or to the small roll shafts 50, 74. The reason for this lies in the fact that as the upper shaft 41 is raised by the screw shafts 64 and 106, the worm wheel or worm gear 39 merely rolls upward along the elongated worm 37, thus continuing the driving connection despite the change in separation.

The mechanism shown in Figure 4 employing the worm drive, and including the elongated worm 37, not only gives less back lash than conventional gearing, but also is more rigid, smoother operating, gives a greater speed reduction between the drive shaft 35 and the roll shafts 40, 41 or 50, 74, and imparts more power to the rolls themselves. At the same time, as previously stated, the driving connection between the drive shaft 35 and the roll shafts 40, 41 or 50, 74 is not interrupted even though the shafts are moved toward or away from one another, since the worm gear 39 rolls along the elongated worm 37 while the adjustment is being made.

If it is desired to change rolls 15 and 16, such as to replace worn rolls or to adapt the machine to rolling workpieces of different configuration, the bolts 84 are unscrewed and withdrawn (Figure 2) whereupon the bolts 26 on the outboard rest 14 are likewise withdrawn so as to permit the outboard rest 14 to be moved outward until the conical ends of the arbors 87 clear the mouths of their conical sockets 80 and 116, whereupon the rolls 15 and 16 and their arbors 87 may be lifted out of the machine and replaced by other arbors as desired. When the new arbors are in position, the outboard rest 14 is moved back toward the housing 13 (Figure 2) so that the tapered ends of the arbors 87 move into their conical sockets, whereupon the bolts 84 are inserted through the bores 118 and 88 and their threaded ends 63 are tightened in the threaded bores 82. This draws the oppositely tapered conical sockets 80 and 116 against the correspondingly and oppositely tapered arbor portions 86 and 94, tightly clamping this assembly together, with the tongues 77 entering the slots 122 in the enlargements 89 (Figure 1). In the case where the smaller rolls are employed, the tongues 79, of course, enter corresponding grooves in the small roller arbors (Figure 1). The hold down bolts or screws 26 are then reinstated in the slots 25 of the outboard rest 14 (Figure 1) and tightened down, thereby completing the securing of the parts in assembly as shown in Figures 1 and 2.

What I claim is:

1. A roll assembly for a rolling mill, comprising an arbor having tapered approximately conical opposite end portions, a roll drivingly

mounted on said arbor intermediate said conical end portions, a roll driving shaft having an approximately conical socket therein matingly receiving one of said conical end portions, a bearing member also having an approximately conical socket therein matingly receiving the other conical end portion, said conical arbor end portion tapering outwardly away from said roll toward said shaft and bearing member sockets respectively, and said sockets flaring inwardly toward 10 said roll, said arbor and said bearing member each having a longitudinal bore therethrough, and a fastener mounted in said bores said fastener detachably securing said bearing member and said arbor to said roll driving shaft and urging said conical end portions and said conical sockets into engagement with one another.

2. A roll assembly for a rolling mill, comprising an arbor having tapered approximately conical opposite end portions, a roll drivingly mounted 20 on said arbor intermediate said conical end portions, a roll driving shaft having an approximately conical socket therein matingly receiving one of said conical end portions, a bearing member also having an approximately conical socket 25 therein matingly receiving the other conical end portion, said conical arbor end portion tapering

outwardly away from said roll toward said shaft and bearing member sockets respectively, and said sockets flaring inwardly toward said roll, said roll driving shaft having a longitudinal threaded bore therein, said arbor and said bearing member having a longitudinal bore therethrough coaxial with said roll driving shaft bore, and a fastener mounted in said bores and having a threaded portion threadedly engaging said threaded bore said fastener detachably securing said bearing member and said arbor to said roll driving shaft and urging said conical end portions and said conical sockets into engagement with one another.

JOSEPH D. KISS.
